[57] CLAIM

The ornamental design for a guitar shoulder strap, as shown and described.

DESCRIPTION

FIG. 1 is a front perspective view of a guitar shoulder strap showing my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The broken lines showing a fastener is for illustrative purposes only and forms no part of the claimed design.

FIG 3**FIG 4****FIG 1****FIG 2***FIG 5*

FIG 6
